UNITED STATES PATENT OFFICE.

FRED S. COULTER, OF LIVONIA, INDIANA, ASSIGNOR OF THIRTY ONE-HUNDREDTHIS
TO WILLIAM F. GUTHRIE, OF CAMPELLSBURG, INDIANA.

AUTOMATIC EXCHANGE SYSTEM FOR THE TRANSMISSION OF INTELLIGENCE.

1,088,541.

Specification of Letters Patent.

Patented Feb. 24, 1914.

Application filed April 9, 1913. Serial No. 759,994.

To all whom it may concern:

Be it known that I, FRED S. COULTER, a citizen of the United States, residing at Livonia, in the county of Washington and State of Indiana, have invented new and useful Improvements in Automatic Exchange Systems for the Transmission of Intelligence, of which the following is a specification.

10 This invention relates to improvements in exchange systems for the transmission of intelligence and has particular application to an automatic system of this character.

In carrying out the present invention, it 15 is my purpose to provide an automatic exchange system for the transmission of intelligence by means of which any one set of a plurality of sets of transmitting and receiving instruments may be automatically connected up with any other set of such instruments so that the operators thereof may 20 communicate with each other, thereby avoiding the use of manually operated exchange systems.

25 It is also my purpose to provide an automatic exchange system which will be found especially useful for interconnecting subscribers' stations and which will be constructed in such manner that each subscriber 30 will have complete control over the automatic exchange so that such subscriber may have talking communication with any other subscriber.

Furthermore, I aim to provide an automatic exchange system for the transmission of intelligence which will embrace the desired features of simplicity, efficiency, durability and convenience and which may be installed and maintained at a minimum expense and readily and conveniently operated by the persons having control of the instruments leading into the exchange.

With the above and other objects in view, the invention consists in the construction, 45 combination and arrangement of parts hereinafter set forth in and falling within the scope of the claims.

In the accompanying drawings; Figure 1 is a diagrammatic view of an exchange system constructed in accordance with my present invention. Fig. 2 is a view in elevation of a subscriber's telephone set. Fig. 3 is a fragmentary sectional view through a sub-

scriber's telephone set showing the indicator used in my system. Fig. 4 is a similar view 55 through the subscriber's telephone set showing the controller. Fig. 5 is a longitudinal sectional view through the casing housing the interconnecting devices of the various sets of instruments showing the means for 60 controlling and rotating such interconnecting devices. Fig. 6 is a cross sectional view through the casing showing the various interconnecting devices in operative position. Fig. 7 is a plan view of the inner surface of 65 one-half of the casing, showing the arrangement of the jacks. Fig. 8 is an enlarged plan view, partly in section, of one pair of the plugs and the operating means therefor, and Fig. 9 is an enlarged fragmentary 70 sectional view through the casing showing one of the jacks.

Referring now to the accompanying drawings in detail, A and B designate subscribers' stations, while C indicates the exchange station. In the present instance, the subscribers' stations A and B are each in the form of a telephone station including a transmitter 1 and a receiver 2. Leading from each subscriber's station into the central station are 80 line wires 3, 3, while located in the exchange station C are the interconnecting devices of my improved automatic exchange system. In the present instance, these interconnecting devices are housed within a cylindrical 85 drum or casing 4 composed of a longitudinal section of insulating material 5 and a similar section of metal or the like 6, the confronting longitudinal edges of the sections being formed with outwardly extending 90 flanges 7 formed with alining apertures to receive securing bolts or the like 8 whereby the sections are held in casing or drum formation. Suitably arranged within this casing 5 is a spring motor 9 or other form of 95 operating means, while journaled in the opposite end walls of the cylinder approximately centrally thereof is a longitudinal shaft 10 having a gear wheel 11 keyed thereon and meshing with a pinion 12 adapted to 100 be rotated by the motor 9. The shaft 10 supports and is adapted to initially operate certain elements of the interconnecting devices and for this purpose has loosely mounted thereon a series of collars 13 spaced apart 105 along the length of the shaft and adapted to

move with the latter and enable the latter to move independently thereof when conditions warrant.

In order that the shaft may impart movement to the collars and such shaft rotate independently thereof, springs 14 are coiled about the shaft and each has one end thereof suitably secured to one face of one of the collars and the opposite end fastened to the shaft. Appropriately fastened to each collar 13 at diametrically opposite points and insulated therefrom by means of strips or insulation 15, are arms 16, 16 depending from the collar and spaced apart in parallelism, the upper extremities of the arms being concaved to conform to the configuration of the collars at the points of connection. The arms of each pair are each formed with a socket 17 opening into the lower end thereof, while in open communication with such socket and coaxial therewith is a circumferentially reduced bore 18 extending well into the respective arm 16 and slidably mounted within such bore 18 is a shank 19 having the lower end thereof headed as at 20 and disposed within the socket 17, while depending from the headed end 20 of the shank and coaxial with the shank is a plug 21 slidably mounted within the socket 17 and adapted to be moved outwardly of such socket by way of the open end thereof, the open end of the socket being preferably closed by means of a cap 22 threaded thereto and formed with an aperture through which the plug moves. Surrounding each plug 21 within the respective socket 17 is a coiled expansion spring 23 having one end bearing against the head 20 on the shank 18 and the opposite end abutting the confronting face of the cap 22, such spring acting to hold the plug normally in retracted position. It will be seen that as the shaft 10 rotates the arms 16 thereon and the plugs carried by such arms will move with the shaft and in an arcuate path incident to the connections between the arms and shaft. Arranged in an arcuate path immediately adjacent to the path of movement of each pair of plugs is a plurality of pairs of jacks 24 embedded in the insulated section of the drum or cylinder, each jack being composed of a cup-shaped member 25 having a marginal flange 26 countersunk in the insulating material so that the open end of the jack will lie flush with the respective section of the drum, the side wall of the cup-shaped member being convexed longitudinally as at 27 so that when the respective plug enters the jack an efficient contact will be made.

In the present instance, I have shown my automatic exchange system as having a capacity of eight sets of subscribers' instruments, and the line wires 3, 3 of each set of instruments have the free terminals thereof tapped onto the arms 16, 16 of a pair of the

plugs, while tapped onto each pair of jacks adapted to receive the respective pair of plugs are the line wires of the remaining sets of instruments with which the particular set of instruments may have talking communication. In other words, the pair of plugs of each set of instruments may be thrown into the sockets adjacent to the path of movement thereof of any other set of instruments so that the calling subscriber will have talking communication with the called subscriber. Thus, it will be seen that, in the present instance, seven pairs of jacks are disposed adjacent to the path of movement of each pair of plugs, as clearly illustrated in Fig. 7 of the drawings.

The shaft 10 is normally held against movement under the action of the motor 9 by means of a controlling mechanism comprising a disk 28 suitably fastened to the shaft and formed with an annular row of apertures 29 adapted to receive a pin 30 formed on one end of a lever 31 fulcrumed between its ends upon a bracket 32 suitably fastened to the interior of the drum, the pin 30 on the lever being normally held in the aperture alining therewith by means of a spring 33 or other form of tension device having one end connected to the bracket and the opposite end fastened to the free extremity of the lever. Fastened to this lever 31 adjacent to the pin end thereof is an armature 34 disposed within the influence of an electro magnet 35 carried by a bracket secured to the interior of the drum or cylinder and connected in series with an indicator located at each subscriber's station, said circuit including a common conductor 36 connected to the winding of the magnet 35 and having one side thereof grounded as at 37 and the opposite side leading into a terminal box 38 from which latter lead individual conductors 39 each running through a subscriber's station and including in series with such station a source of energy as a battery 40, an indicator controlling magnet 41, and a controller 42, the latter being herein shown as a key, the free terminal of each conductor 39 being grounded as at 43.

In each subscriber's station is an indicator composed of a dial 44 mounted upon an arbor 45 adapted to be rotated by a spring or other form of motor 46, and a finger 47 overlying the face of the dial. The face of the dial 44 is formed with an annular row of apertures 48 disposed adjacent to the periphery of such dial and designed to receive a pin 49 formed upon one end of a lever 50 having the other end thereof fulcrumed as at 51 upon a suitable bracket, a spring 52 holding the pin 49 on the lever 50 in engagement with the alining aperture in the dial. Upon this lever 50 is an armature 53 disposed within the influence of the respective magnet 41. The shaft 10

and the dial 44 of the indicator at each station are so timed as to run synchronously so that when the controller 42 in the respective subscriber's station is closed, the circuit will be energized to energize the magnets 41 and 35 and thereby withdraw the pin 39 from engagement with the respective aperture in the dial 44 of the indicator at such subscriber's station, and the pin 30 from engagement with the respective aperture in the disk 28 at the central office. In this condition of the system, the spring motors 9 and 46 act to rotate, respectively, the disk 28 and the dial 44, and should the subscriber at the station wish to have talking communication with another subscriber, the calling subscriber will hold the controlling circuit closed until the dial 44 has rotated a distance corresponding to the number of the called subscriber's telephone. To illustrate, assuming the line wires 3 of the station A to include the pair of arms 16 at the end of the shaft 10 remote from the motor A in Fig. 5, and the line wires 3 of station B, to include the last pair of jacks in each series or row of such jacks with which the plugs of all other lines coöperate, the operator or subscriber at station A will close the respective key 42 thereby permitting the shaft and dial of the indicator to rotate. When the dial has rotated a distance corresponding to the length of the row of jacks, such subscriber will release the key and so open the circuit thereby locking the shaft 35 and dial against further movement. Thus, the respective pair of plugs are initiated into service and capable of being thrown into the alining pair of jacks of the called phone.

In order that each pair of plugs may be thrown outwardly from the respective arms and into the alining jacks, the pairs of arms each carry an electromagnet 54 disposed between the same and controlling an armature 55 carried by a cross piece 56 formed of insulating material and having the opposite ends thereof bifurcated and embracing the opposite sides of the respective pair of arms 16, the bifurcated ends of the cross piece 56 being connected to the upper ends of the shanks in the respective pair of arms 16 through the medium of pins 57 passed through the free extremities of the limbs of the bifurcated ends of the cross piece and 55 the shanks 19, such pins being adapted to work within slots 58 formed in the arms 16. Thus, when any one of the magnets 54 is energized, the armature 55 controlled thereby will be attracted and the cross piece actuated with the effect to slide the shanks 19, 19 within the bores 18 and so throw the plugs 21 outwardly of the respective end of the arms and into the alining pair of jacks. Each magnet 54 has the core thereof in the form of a permanent magnet so that when

the armature 55 has been attracted it will be held against return to normal position under the action of the springs 23 after the winding of the magnet 54 has been de-energized. The coil of each magnet 54 is connected in an actuating circuit including a source of energy such, for instance, as an electric battery 59 located at the respective station, a pole changer 60, the line wires of conductors 3 of such station, the respective pair of arms 16, 16, and an impedance coil 61, the battery pole changer, impedance coil and respective magnet 54 being all connected in series in this circuit, as clearly illustrated in Fig. 1 of the drawings.

Subsequent to the initial movement of the plugs under the action of the motor 9 and shaft 10 as previously described, the operator or subscriber at the particular calling station will throw the pole changer so that the current of the battery 59 will flow through the winding of the magnet 54 and so set up a magnetic flux of a strength great enough to act upon or penetrate the air gap between the pole of the respective magnet and the armature 55, with the effect to attract such armature and so throw the plugs into the registering or alining jacks. Succeeding this operation, the calling subscriber breaks the circuit of the magnet 54 at the pole changer and so deenergizes the winding of such magnet, thereby taking the current of the battery 59 off of the line and out of the talking circuit, the impedance coil 61 acting to prevent the passage of the talking current through the winding of the magnet 54. When the particular subscriber has finished the conversation over the line he manipulates the pole changer so as to reverse the current flow from the battery 59 through the line thereby overcoming the magnetic force of the permanent core of the magnet 54 and, as a consequence, the armature 55 is repelled or released so that the springs 23 may react and restore the armature to normal position. After the conversation has ceased, the calling subscriber again energizes the controlling circuit by closing the controller 42 and so permits the shaft 10 to be rotated under the action of the spring motor 9 until the respective indicator advises such subscriber that the parts are in original position.

From the foregoing description taken in connection with the accompanying drawings, the construction, mode of operation and manner of employing my invention will be readily apparent. It will be seen that when two sets of instruments are interconnected so as to establish communication between such instruments the shaft 10 may be caused to rotate independently of and without disturbing the connections between such communicating instruments, owing to the spring connections between the shaft and

the arms carrying the plugs. The arms carrying the plugs are preferably normally arranged as illustrated in Fig. 4 so as to facilitate the interconnecting of the various sets of instruments.

While I have herein shown and described one preferred form of my invention by way of illustration, I desire to have it understood that I do not limit or confine myself to the precise details of construction herein described and delineated, as modification and variation may be made within the scope of the claims without departing from the spirit of the invention. Furthermore, I wish it to be understood that my invention in its useful application is not limited to telephone lines as the same may be employed in conjunction with telegraph apparatus and analogous devices whereby selective interconnection between instruments is desired. It will also be observed that the range or capacity of my improved automatic exchange system may be varied in accordance with the exigencies or circumstances of each particular case.

I claim:

1. In an automatic exchange system for the transmission of intelligence, sets of transmitting and receiving instruments, an automatic exchange mechanism interposed between said sets of instruments and including a plurality of interconnecting devices each connected to one set of said instruments and leading to another set, and an actuating device common to all of said interconnecting devices whereby the same may be initially operated, an indicator for each set of instruments designed to move in synchronism with said actuating device, connections between each indicator and said actuating device, a controller at each station whereby the respective indicator and the actuating device may be operated to initially actuate the respective interconnecting device, and means for subsequently operating the respective interconnecting device independently of the remaining devices to establish communication between the calling and called sets of instruments.

2. In an automatic exchange system for the transmission of intelligence, sets of transmitting and receiving instruments, an automatic exchange mechanism interposed between said sets of instruments and including a plurality of interconnecting devices each connected to one set of said instruments and leading to another, an actuating device common to all of said interconnecting devices whereby the same may be initially actuated, and means for subsequently operating the respective interconnecting device independently of the remaining devices to establish communication between the calling and called sets of instruments.

3. In an automatic exchange system for the transmission of intelligence, sets of transmitting and receiving instruments, an automatic exchange mechanism interposed between said sets of instruments and including a drum, a shaft journaled in said drum and capable of longitudinal movement therein, pairs of plugs carried by said shaft and spaced apart along the length thereof and adapted to rotate therewith in an arcuate path, pairs of contacts carried by the interior of said drum and disposed in an arcuate path adjacent to the path of movement of each plug, connections between each pair of plugs and the respective transmitting instruments of the sets, connections between each pair of jacks and the receiving instruments of the sets, means for rotating said shaft whereby any one pair of plugs may be brought into registration with a pair of jacks, and means for moving the respective pair of plugs radially of the shaft and into the alining jacks whereby the calling and called sets of instruments may be placed in communication.

4. In an automatic exchange system for the transmission of intelligence, sets of transmitting and receiving instruments, an automatic exchange mechanism interposed between said sets of instruments and including a drum, a shaft journaled in said drum and capable of rotary movement therein, pairs of plugs carried by said shaft and spaced apart along the length thereof and adapted to rotate therewith in an arcuate path, pairs of contacts carried by the interior of said drum and disposed in an arcuate path adjacent to the path of movement of each plug, connections between each pair of plugs and the respective transmitting instruments of the sets, connections between each pair of jacks and the receiving instruments of the sets, means for rotating said shaft whereby any one pair of plugs may be brought into registration with a pair of jacks, means for moving the respective pair of plugs radially of the shaft and into the alining jacks whereby the calling and called sets of instruments may be placed in communication, and connections between each pair of plugs and said shaft whereby the latter may be rotated to move the inactive plugs relatively to those in use.

5. In an automatic exchange system for the transmission of intelligence, sets of transmitting and receiving instruments, an automatic exchange mechanism interposed between said sets of instruments and including a drum, a shaft journaled in said drum longitudinally thereof and capable of rotation therein, pairs of plugs carried by said shaft and spaced apart along the length thereof and adapted to rotate therewith, pairs of jacks carried by the interior of said drum and disposed in an arcuate path adjacent

to the path of movement of each plug, connections between each pair of plugs and the respective transmitting instruments of the sets, connections between each pair of jacks and the respective receiving instruments of the sets, a spring motor for rotating said shaft whereby any one pair of plugs may be brought into registration with a pair of jacks, and means for moving the respective 5 pair of plugs radially of the shaft and into the alining jacks whereby the calling and called sets of instruments may be placed in communication.

6. In an automatic exchange system for the transmission of intelligence, sets of transmitting and receiving instruments, an automatic exchange mechanism interposed between said sets of instruments and including a drum, a shaft journaled in said drum longitudinally thereof and capable of rotation therein, pairs of plugs carried by said shaft and spaced apart along the length thereof and adapted to rotate therewith, pairs of jacks carried by the interior of said drum and disposed in an arcuate path adjacent to the path of movement of each plug, connections between each pair of plugs and the respective transmitting instruments of the sets, connections between each pair of jacks and the respective receiving instruments of the sets, a spring motor for rotating said shaft whereby any one pair of plugs may be brought into registration with a pair of jacks, a magnet having a permanent magnetic core and controlling each pair of plugs, and means for energizing said magnet whereby the respective pair of plugs may be moved radially of the shaft and into the alining jacks to establish communication between the calling and called sets of instruments.

7. In an automatic exchange system for the transmission of intelligence, sets of transmitting and receiving instruments, an automatic exchange mechanism interposed between said sets of instruments and including a drum, a shaft journaled in said drum longitudinally thereof and capable of rotation therein, pairs of plugs carried by said shaft and spaced apart along the length thereof

and adapted to rotate therewith, pairs of jacks carried by the interior of said drum and disposed in an arcuate path adjacent to the path of movement of each plug, connections between each pair of plugs and the respective transmitting instruments of the sets, connections between each pair of jacks and the respective receiving instruments of the sets, a spring motor for rotating said shaft whereby any one pair of plugs may be 55 brought into registration with a pair of jacks, a magnet having a permanent magnetic core and controlling each pair of plugs, an electric circuit including said magnet and adapted to energize the same to throw 60 the respective pair of plugs into the alining jacks, and a pole changer whereby the flow of current through the circuit of said magnet may be reversed to overcome the action 65 of the core thereof.

8. In an automatic exchange system for the transmission of intelligence, subscribers' stations, an automatic exchange mechanism interposed between said stations and including a plurality of interconnecting devices, 75 each connected to one of said stations and leading to another, an actuating device common to all of said interconnecting devices whereby the same may be initially actuated, an indicator at each station designed to move 80 synchronously with said actuating device, connections between each indicator and said actuating device, a controller at each station whereby the respective indicator and actuating device may be operated to initially operate the respective interconnecting device, an electromagnet for subsequently operating the respective interconnecting device independently of the remaining devices to establish communication between the calling 85 and called stations, and means for energizing, deenergizing, and reversing the flow of current through said magnet substantially as and for the purpose set forth.

In testimony whereof I affix my signature 90 in presence of two witnesses.

FRED S. COULTER.
